FIG. 3.

INVENTOR

Hikojiro Kobayashi

UNITED STATES PATENT OFFICE.

HIKOJIRO KOBAYASHI, OF LOS ANGELES, CALIFORNIA.

SALT AND PEPPER SHAKER.

1,254,409.

Specification of Letters Patent. Patented Jan. 22, 1918.

Application filed February 8, 1917. Serial No. 147,486.

To all whom it may concern:

Be it known that I, HIKOJIRO KOBAYASHI, a subject of the Emperor of Japan, residing at Los Angeles, in the county of Los Angeles and State of California, have invented new and useful Improvements in Salt and Pepper Shakers, of which the following is a specification.

My invention relates to improvements in salt and pepper shakers, and the objects of my improvements are, to provide a convenient shaker by which salt or pepper can be scattered and spread; to prevent the salt from becoming wet; to close the salt receptacle automatically; to provide a double receptacle, one compartment for salt and the other for pepper; to provide an automatically moving closure over the opening of the two compartments keeping the salt receptacle automatically closed preventing the salt from becoming wet, the closure being provided with openings matching with the openings in the two compartments in such a manner that a series of openings in the closure match with the openings in one compartment while a second series of openings in the closure are so arranged that they do not match with the openings in the second compartment before the first series of openings has been shifted far enough that the openings in the first compartment are closed by the closure; the invention consisting in the construction, combination and arrangement of devices hereafter more fully described and claimed, and illustrated in the accompanying drawing, in which—

Figure 1 is a vertical cross section of my device.

Fig. 2 is a side view.

Fig. 3 is a top view.

Similar numbers refer to similar parts throughout the papers.

The receptacle 1 in the drawing is provided with the compartment 2 for salt and the compartment 3 for pepper. Fill-openings 4 are provided in the bottom of the two compartments of the shaker or receptacle which are normally closed by the plugs 5. Discharge openings 6 are provided in the upper end of the compartment for the

salt, and discharge openings 7 are provided in the upper end of the compartment for the pepper. A recess 8 is formed in the receptacle or shaker outside of the compartments at the top end adjacent to the discharge openings. A closure plate 9 is slidably mounted in the recess transversely above the discharge openings. The closure plate is continued, bent downwardly and attached at the lower end of the shaker as indicated at 10. A spring 11 is disposed between the downwardly extending end 12 of the closure plate and the shaker. The closure plate 9 is provided with holes or perforations 13 matching with the discharge openings 7 in the top end of the compartment for the pepper. The perforations or holes 14 are provided in the closure plate to match with the discharge openings 6 in the top end of the compartment for the salt, but normally these holes 14 are shifted out of alinement, the closure plate 9 normally keeping the discharge openings 6 closed preventing the salt from becoming wet or damp.

Having this salt and pepper shaker in the hand, it is operated by pressing the downwardly extending end 12 or releasing the same thereby shifting the closure plate 9 to match the holes 13 in the closure plate 80 with its discharge openings 7 in the pepper compartment, or, to match the holes 14 in the closure plate with the discharge openings 6 in the salt compartment.

The end 15 of the closure plate 9 is bent forming a stop for the shifting of the closure plate.

Having thus described my invention, I claim:

A salt and pepper shaker comprising separate compartments for salt and pepper, the separate compartments having separate discharge openings, two opposing sides of the shaker having extension ends projecting upwardly and overlapping the top to a suitable extent for forming a guiding member for a closure plate, a closure plate slidably mounted over the top below the guiding members terminating in a bent end engaging over the edge of the shaker for termi- 100

nating the shifting of the closure plate, the opposite end of the closure plate terminating in a spring member also bent over the shaker on the opposite side of the shaker 5 top, and spaced from the shaker side and connected to the shaker side, all substantially as described.

In testimony whereof I hereunto affix my signature in the presence of two witnesses.

HIKOJIRO KOBAYASHI.

Witnesses:

MASAYOSHI KOJIMA,
F. K. KOGH.
